UNITED STATES PATENT OFFICE.

FREDERICK H. FELGER, OF NEWARK, NEW JERSEY, ASSIGNOR TO F. & F. FELGER, INC., OF NEWARK, NEW JERSEY.

DESIGN FOR A PLATE FOR MOUNTING GEMS IN JEWELRY.

55,597.

Specification for Design.

Patented July 6, 1920.

Application filed March 16, 1920. Serial No. 366,421. Term of patent 7 years.

To all whom it may concern:

Be it known that I, FREDERICK H. FELGER, a citizen of the United States, residing at Newark, county of Essex, and State of New Jersey, have invented a new, original, and ornamental Design for a Plate for Mounting Gems in Jewelry, of which the following is a specification, reference being had to the accompanying drawing, forming part thereof.

Figure 1 is a face view of the new and or-

namental plate for mounting gems in jewelry, with prongs of a piece of jewelry and a stone in the plate shown in dotted outline to more clearly illustrate its use.

Fig. 2 is a side view of the plate, and
Fig. 3 is a section taken on line 3—3 in
Fig. 1.

I claim:

The ornamental design for a plate for mounting gems in jewelry, as shown.

FREDERICK H. FELGER.
